UNITED STATES PATENT OFFICE.

ELVER H. SHAW, OF SEDALIA, MISSOURI.

DOOR-CHECK.

1,135,061.

Specification of Letters Patent. Patented Apr. 13, 1915.

Application filed July 26, 1913. Serial No. 781,447.

To all whom it may concern:

Be it known that I, ELVER H. SHAW, a citizen of the United States, residing at Sedalia, in the county of Pettis and State of 5 Missouri, have invented a new and useful Door-Check, of which the following is a specification.

The present invention appertains to door checks, and relates to a novel and improved 10 door check and buffer.

It is the object of the present invention to provide a door check and buffer of such peculiar and unique construction, as to render it adjustable in character, whereby the device 15 may be employed under various circumstances.

Another object of the present invention is to provide a device of the nature indicated which shall be of such construction as to 20 carry out the functions desired in a highly efficacious manner.

It is also within the spirit of the invention to provide a device of the character specified which shall be comparatively simple and in- 25 expensive, the same being capable of manufacture from strips or bars of sheet metal, and being convenient and efficient in its use.

With the foregoing and other objects in view, which will appear as the description 30 proceeds, the invention resides in the combination and arrangement of parts and in the details of construction hereinafter described and claimed, it being understood that changes in the precise embodiment of the 35 invention herein disclosed, can be made within the scope of what is claimed, without departing from the spirit of the invention.

The invention has been illustrated in its preferred embodiment in the accompanying 40 drawing, wherein:

Figure 1 is an elevation of the device, as in use. Fig. 2 is a plan view thereof. Fig. 3 is a central longitudinal section of the device. Fig. 4 is a perspective view of the 45 door carried member.

In carrying out the present invention, reference being had in detail to the drawing, the device is constructed of three members, viz., a member 1 which is attachable to a 50 base or mop board B, a floor, or other supporting member, a buffer and catch member 2 carried by the member 1, and a member 3 adapted to be carried by the door or other swinging structure D. These members are 55 each fashioned from a strip or bar of suit-

able metal, having the requisite resiliency and other qualities.

The supporting member 1 embodies a metallic strip or ribbon 4 having its intermediate portion doubled and projecting angularly to provide a horizontal ear 5, the strip 4 having its end portions disposed vertically and apertured, in order that the end portions of the strip 4 may be secured to a mop board B or other supporting structure, by 60 means of nails, screws or other securing members. The supporting member also preferably includes a horizontal strip or bar 6 having a slot at its central portion receiving the ear 5, and having apertures at its ends 65 for facilitating the attachment of the strip 6 to the mop board. The ear 5 carries a clamping bolt 7 for the pivotal attachment of the buffer and catch, as will hereinafter appear. 70

The buffer and catch is fashioned from a strip or ribbon of metal, the intermediate portion of which is formed into a circular loop 8. Those portions of the strip or bar intermediate the loop 8 and the terminals 80 are formed into a rectangular loop or frame 9 loosely surrounding the loop 8. The bends between the ends of the loops 8 and 9 are reflexed or bent back inwardly, to provide the beads 10 forming a mouth for the reception of the head of the dog-carried member 3, as will hereinafter appear. The loop or frame 9 opposite the beads 10 is provided with the ears 11, comprising the meeting terminals of the strips from which the buffer and catch is formed, the ears 11 being in alinement with the mouth formed by the beads 10 and being apertured and pivoted to the bolt 7 over the upper and lower faces of 90 the ears 5. 95

Coming to the door-carried member, the same is fashioned from a strip or ribbon 12 having its intermediate portion doubled and bent into a cuneiform head 13 of a length slightly less than the diameter of the circular loop 8, the end portions of the strip 12 being adapted to be disposed vertically and being apertured for the insertion of the securing members to secure the strip 12 to the face or side of a door or other swinging structure. 100

In employing the present device, in connection with a hinged door, the supporting member 1 is secured to the base or mop board B in the path of the free portion of 110

the door D, and the buffer and catch 2 is swung so as to assume a position at right angles to the door, when the door is swung thereagainst, as seen in Fig. 2. The member 3 is then secured to the door, so that the head 13 is adapted to enter the mouth of the member 2. The bolt 7 is then tightened, to clamp the member 2 in position, and the device is then in condition for operation.

10 When the door is swung open, the tip of the head 13 enters the mouth of the member 2, and as the head 13 is forced home, the beads 10 will separate, under the tension of the loops 8 and 9, and will snap in back of the shoulders of the head 13, to hold the door in open position. It is to be observed that when the door is swung open against the member 2 the forward ends of the loops 8 and 9 will yield, so as to arrest or check the

20 movement of the door in an efficient manner, the member 2 being of such unique construction as to thus carry out this function. Particular attention is directed to the fact that when the door is swung open, the head 13

25 of the door-carried member is designed to forcibly enter the mouth of the buffer and catch, whereby the outer loop 9 will yield first to enable the inner loop 8 to contact therewith and yield under greater pressure,

30 and finally, upon still greater pressure, the head 13 will contact with the inner loop and yield. Thus, the door may be gradually brought to a standstill, by the successive yielding and bowing actions of the loops 9

35 and 8 and head 13. When the door is manually swung to closed position, the head 13 will be retracted from the member 2, the beads 10 yielding to permit the head to withdraw from the member 2, as will be ap-

40 parent.

From the foregoing, taken in connection with the drawing, the advantages and capabilities of the present invention will be apparent to those versed in the art, attention being directed to the fact that the catch and buffer 2 is pivotally carried by the supporting member 1, in order that the device may be adjusted to suit the various conditions.

Thus, the member 2 may be set so as to properly engage the door-carried member 3 irrespective of the particular angle the door assumes when in open position. Attention is also directed to the fact that the supporting member 1 may be secured on the floor, so that the ear 5 stands vertically, the member 2 being swung to a horizontal or other position, to properly receive the head 13 of the member 3 which is secured properly to the door. This method of employing the present device will be apparent without a lengthy description or illustration thereof, and merely illustrates another capability of the improved device.

Having thus described the invention, what is claimed as new is:—

In a door check, a buffer and catch fashioned from a resilient metallic strip, the intermediate portion of which is bent to form a yieldable circular inner loop, the portions of the strip intermediate the said loop and ends being bent to form a yieldable rectangular outer loop loosely surrounding the inner loop, and to form a mouth, the ends of the outer loop meeting and being bent to form ears, the ears being in alignment with the said mouth, a supporting member to which the ears are secured, and a door-carried member fashioned from a metallic strip having its intermediate portion doubled and bent to form a yieldable cuneiform head of a length slightly less than the diameter of the inner loop, and designed to forcibly enter the aforesaid mouth whereby the outer loop will yield first to enable the inner loop to contact therewith and yield under greater pressure, and whereby the said head will then contact with the inner loop and yield under still greater pressure.

In testimony that I claim the foregoing as my own, I have hereto affixed my signature in the presence of two witnesses.

ELVER H. SHAW.
